UNITED STATES PATENT OFFICE.

GEORGE E. FARLINGER, OF DETROIT, MICHIGAN, ASSIGNOR TO BRISCOE MANUFACTURING COMPANY, OF DETROIT, MICHIGAN, A CORPORATION OF MICHIGAN.

RADIATOR.

1,138,367.

Specification of Letters Patent.

Patented May 4, 1915.

Application filed December 2, 1910. Serial No. 595,275.

To all whom it may concern:

Be it known that I, GEORGE E. FARLINGER, a citizen of the United States of America, residing at Detroit, in the county of Wayne 5 and State of Michigan, have invented certain new and useful Improvements in Radiators, of which the following is a specification, reference being had therein to the accompanying drawings.

10 The invention relates to radiators particularly designed for use on motor vehicles and consists in the construction as hereinafter set forth.

15 In the drawings, Figure 1 is a perspective view of a portion of the radiator showing the manner of construction thereof; Fig. 2 is a vertical longitudinal section thereof; Fig. 3 is a front elevation.

20 The invention relates more particularly to radiators of that type in which the water to be cooled is passed through vertical pipes while horizontally extending fins secured to said pipes serve to increase their radiating efficiency. In appearance such a radiator 25 presents to view the horizontally extending parallel edges of the radiating fins but the effect is not as pleasing to the eye as other constructions in which the front is divided into squares.

30 It is one of the objects of the present invention to improve the appearance of the radiator and at the same time to increase the strength of the construction and its radiating efficiency, these objects being accomplished as follows:

35 A represents the water circulating tubes of the radiator which as shown are arranged in staggered relation about each other, B are the radiating fins which are apertured 40 to be sleeved upon the tubes A and are arranged to extend horizontally. The front edges of these fins are strengthened and given a more substantial appearance by forming beads thereon preferably by bending 45 the sheet metal about a plurality of strengthening strips C which may be formed of a stiffer metal than that composing the fins. Thus as shown in Fig. 3 the front edges of the fins have the appearance of a 50 solid bar formed of thicker metal than the thickness of the fins.

To produce the desired square effect the

beads or reinforced edges of the fins are provided with a plurality of slots D therein preferably spaced from each other a distance equal to the spacing between the fins. In these slots are placed vertically extending bars E the depth of which is slightly less than the beads so that the slots D will not completely sever the reinforcement strips C. 55 These bars E are secured to the ribs preferably by dipping in solder and subsequently the whole front is surfaced so as to bring the edges of all the bars and fins in the same plane. Thus an appearance is produced 60 which can scarcely be distinguished from a square tube radiator construction.

In addition to the improvement in appearance, the construction above described 65 greatly strengthens the radiator. It is 70 obvious that the thin metal of the fins possess very little strength and the slightest blow on the radiator front will bend and distort the metal. With my improved construction however, the reinforcement of the 75 edges of the fins due to the strips inclosed in the beads and also the cross-bars secured to the fins will produce a very strong structure not easily disfigured.

Still another advantage of the construction 80 is the increased radiating surface afforded by the vertical bars E, and as these are secured to the fins by soldering the heat conduction thereof is rapid and the temperature of all the indirect radiating surfaces 85 equalized.

What I claim as my invention is:

A radiator comprising liquid circulating tubes, fins extending transversely thereof of having an integral portion at their forward edge bent to form beads, reinforcing strips of stiffer metal inclosed in said beads, 90 said reinforcing strips and beads being slotted, the depth of the slot being slightly less than the depth of the reinforcing member, 95 and bars extending transversely to said fins, engaging said slots.

In testimony whereof I affix my signature in presence of two witnesses.

GEORGE E. FARLINGER.
